POSITION REPRODUCING MECHANISM

James D. Tear, Great Neck, N. Y., assignor to
 Ford Instrument Company, Inc., Long Island
 City, N. Y., a corporation of New York

Application March 28, 1942, Serial No. 436,685

9 Claims. (Cl. 172—239)

1

The invention relates to mechanisms for reproducing position and particularly to such mechanisms of the follow-up type in which the transmission system operates a control member for a power unit termed a servo-motor.

The invention is applicable with self synchronous transmissions in which the torque of the receivers is zero when they are in synchronism with their transmitters, and which employ dual transmissions of different speed ratios, the units of positional value transmitted by the low speed transmitters being relatively large or coarse, and those transmitted by the high speed transmitters being relatively small or fine.

A characteristic of embodiments of the invention is the fact that there is but a single control member for the amplifying power unit, and that this control member is operated by a drive which is selectively controlled by the fine and coarse receivers depending upon the positional error, that is, the extent to which the driving or motion receiving member fails to synchronize or agree in position with the original or motion transmitting member; and it is with the proper transfer and maintenance of this selective control that the invention is more especially concerned.

In such follow-up systems the power unit operates reversely upon the control member to shut off the power when the transmitted movement is completely reproduced. The movement of the control member is usually limited in both directions and a relief connection or yieldable coupling in the drive from a receiver to the control member frees the receiver rotor from limitation in synchronizing with its transmitter. The construction of this relief connection is such that the drive for the control member is biased to a positional relation with the receiver rotor and is self synchronous or self-correcting within the range of a limited error beyond which it tends to increase the error in order to return to biased relation, by returning in the wrong direction.

In accordance with this invention an auxiliary power unit arranged under the control of the coarse receiver is connected to supplement the drive to the control member and to cause the coarse receiver to assume charge of the control member for the servo-motor as long as the error exceeds the limited amount. The auxiliary power unit may be an electric motor the energizing circuit of which includes a pair of contacts one of which is moved with the coarse receiver and the other of which is moved in the same path by the drive for the servo-motor control member operated by the fine receiver, and at the same ra-

2

tio of movement thereto that the coarse receiver bears to the fine receiver. The two contacts are spaced a predetermined distance when the relief connection is in its biased position, and the distance is decreased in proportion as the relief connection departs from its biased position until the contacts engage whereupon the auxiliary motor is energized and assumes control of the control member. This occurs before the condition is reached where the relief connection would jump to a false position and thus throw the control member further out of phase relation with the fine receiver rotor.

The invention also contemplates suitable clutching means in the connection with the auxiliary motor which is engaged only when the coarse receiver is in charge and thus relieves the fine receiver of the load of the armature so long as the fine receiver is in charge.

20 This invention is adapted for actuating a servo-motor control of the type in which the velocity at which the power driven response approaches the velocity of the transmitted movement, such as a signal, is limited to some function of the discrepancy between the received signal and the power driven response. Such a type of control is desirable when synchronizing the response with the signal as in starting up the system or whenever the response may depart from 30 the signal for any reason, such as a shift of the receivers to a different pair of transmitters.

Other objects and advantages of the invention will appear from the following description of the embodiment of the invention shown in the accompanying drawings.

Fig. 1 shows diagrammatically an embodiment of the invention used in connection with a simple form of servo-motor control.

Fig. 2 shows a modified form of servo-motor control in which the servo-motor is controlled so that the velocity at which the error in response is removed is a function of the error.

The two speed transmission shown is of the type disclosed for example in the patent to Hewlett and Willard No. 1,559,524. The two transmitters 1 and 2 are geared together by gearing 3 such that motion applied by a motion transmitting member 4 will move the rotor of transmitter 1 at a high speed relative to that of the rotor of transmitter 2, say 36:1. The rotors of the receivers 5 and 6 will have the same ratio of movement.

The rotor of the fine receiver 5 is connected by a shaft 7 to one side of a centralized relief connection or yieldable drive coupling 8 the other

side of which is connected by shaft 9, bevel gears 10 and shaft 11 to one side of a control differential 12. Specifically the coupling 8 is of the construction shown in the patent to Poitras and Tear No. 2,134,483.

A reversible power motor 13, shown as an electric motor, is connected by shaft 14, bevel gears 15 and shaft 16 to a second side of control differential 12, the shaft 14 also being connected to drive the load which it is desired to position in accordance with the transmitted positional value. The third member of differential 12 actuates a directional control member 17, in this case a movable electric contact, which is energized by a source of power 18 and is alternatively connected to the motor 13 by the leads of reversing contacts 19 and 20. The motor 13 is connected to the other side of the power source 18 by a lead 21.

It will be understood that as the rotor of the receiver motor 5 is turned in response to the transmitted value, the contact 17 will be moved to close one or the other of the motor circuits and the power motor will rotate in a direction to position the load in accordance with the movement of the motion transmitting member, and at the same time the movement of shaft 14 will be transmitted to the differential 12 through the shaft 16 and neutralize the input to the differential, thereby opening the contact 17 and stopping the motor 13.

The shaft 22 of coarse receiver 6 is connected through a yieldable coupling 23, similar to coupling 8, to rotate an insulated contact 24 on the end of radial arm 25. The contact 24 cooperates with two insulated contacts 26 and 27 located on opposite sides of the contact 24 and carried by the arm 28 which is mounted for rotation coaxially with the arm 25. The arm 28 is directly connected to and is rotated by a gear 29 which is driven through reduction gearing 30 by a gear 31 on shaft 9. The ratio of the gearing 30 is the same as that of the gearing 3, and hence the rotation of the arm 28 relative to the shaft 9 is the same as the ratio of rotation of the coarse transmitter unit relative to that of the fine transmitter unit.

The shaft 9 carries a gear 32 which is geared with one member 33 of a clutch unit 34. The other member 35 of the clutch unit is rotatably connected to the armature of a reversible electric motor 36 by gears 37 and shaft 38 on which the member 35 is slidably mounted. The clutch member 33 is freely mounted on shaft 38 but is restrained against axial movement. Surrounding shaft 38 is a stationary coil 39 and a field frame 40 of magnetic material. The clutch member 35 and shaft 38 are also of magnetic material and therefore when the coil 39 is energized the member 35 will be pulled into engagement with a friction surface, such as cork, on the member 33. Thus rotation of motor 36 will be communicated through the clutch unit 34 to the shaft 9.

Three slip rings 41, 42 and 43 on the shaft of arm 28 are electrically connected respectively with the center contact 24 driven by coarse receiver 6, and the two contacts 26 and 27 driven by the shaft 9. Brushes contacting these slip rings connect with the windings of motor 36 through leads 44, 45 and 46 respectively. The common lead 44 includes a source of power 47 and the coil 39 in series relation. It is apparent, therefore, that as the contact 24 touches either of contacts 26 and 27 the energizing circuit of motor 36 is closed to produce a torque in one direction or the other, and at the same time clutch

34 is engaged, and that the torque of motor 36 is applied on shaft 9.

The operation will be apparent from the foregoing description. The yieldable drive couplings have on one side a cam and on the other a spring pressed follower, the cam surface tapering in both directions from a high spot to a diametrically opposite low spot. The spring causes the follower to seek the low spot. If the two sides get out of angular agreement so far that the cam rides over the high spot the spring will return the follower to the low spot by a continuation of movement in the same direction and thus further increase the error. In other words the drive is self correcting only up to substantially 180° of error.

It is this fact that determines the spacing of the contacts 26 and 27. The arms 25 and 28 are so set that the contact 24 is midway between contacts 26 and 27 when the couplings are in their biased position. Let it be assumed that power motor 13 lags in its following and hence that the input of shaft 11 into the differential 12 is not counteracted sufficiently fast by the input of shaft 16. The contact 17 will be rotated against either contact 19 or 20 and as the error accumulates the cam follower of coupling 8 will ride up the cam surface against the spring tension. Arm 28 similarly lags but in the reduced ratio, and the spacing of contacts 26 and 27 is so determined that the appropriate one is engaged by the contact 24 just before the cam follower reaches the high spot of the cam and hence before the coupling 8 can jump ahead. The motor 36 is thereby energized, and the clutch being at the same time closed, the motor torque is applied to the shaft 9 in a direction to prevent the shaft from jumping ahead if the error increases and the follower passes over the high spot, and thus from increasing the effect of the error.

Assuming the ratio of 36:1, one complete rotation of the fine receiver or 360° of movement of the member 4 represents one-thirtieth of a complete rotation of the coarse receiver, or 10° of movement of the arm 25. If the follow-up is accurate the contacts 26 and 27 will move along in synchronism with the contact 24 and keep it centralized. However as the follow-up gets out of synchronism the coupling 8 begins to yield and the drive of arm 28 gets correspondingly out of step but at the reduced ratio. When the shaft 9 is 180° out of phase with the shaft 7, the arm 28 is 5° out of phase with the arm 25. The maximum spacing of the contacts 26 and 27 is such that just before that condition is reached the contact 24 engages, but, of course, the spacing may be less.

Conditions arise in use, particularly at the start of the operation, when the disparity between the positions of the motion transmitting and receiving members will greatly exceed the range within which the system is self correcting and which require perhaps one or more complete turns of the fine receiver and a partial turn of the coarse receiver to be fed into the control differential to bring the follower member into positional agreement with the transmitter member. It will be seen that although both the coarse and fine receivers are turning over, the coarse receiver is in control of the input to the differential 12, until the contacts 24, 26 and 27 are satisfied and open the circuit of the motor 36, but when the torque of this auxiliary motor becomes zero the shaft 9 returns to control of the fine receiver and the follow-up motor is thereby sensitively controlled to bring the follower member into exact syn-

chronism, when the contacts 17, 19 and 20 are satisfied and the circuit of the motor 13 is opened.

In the servo-motor control shown in Fig. 2 the contacts 19 and 20 are mounted on an arm 48 extending from a shaft 49 mounted in axial alignment with the shaft on which the contact 17 is mounted. The shaft 49 carries a pinion 50 meshing with a gear 51 on a shaft 52. The shaft 52 has secured to it an arm 53 to the end of which centralizing springs 54 are attached. The shaft 49 also carries a gear 55 which meshes with a pinion 56 connected to drive a drag disc 57. The drag disc is shown as running in a chamber 58 filled with a liquid such as oil, but any form of drag device may be employed. The gear 55 carries a pin 59 adapted to engage a fixed pin 60 and thereby limit the rotation of gear 55 and arm 48 carrying the contacts 19 and 20.

With this form of servo-motor control the centralizing springs 54 will maintain the contacts 19 and 20 in a fixed position during normal operation, that is, when the response represented by shaft 16 remains synchronized with the signal represented by shaft 11. If for any reason the response, represented by shaft 16, does not agree with the signal represented by shaft 11, the contact 17 will displace the contacts 19 and 20 against the centralizing effect of the springs 54. This displacement may correspond to several turns of the fine receiver motor 5 and is only limited by the stop pins 59 and 60. It will be seen that the receiver motor 5 will remain in direct control of the drive 9 even though the response may differ from the signal by an amount represented by several turns of receiver 5. It will also be seen that the contact 24 will remain centered between the contacts 26 and 27 during the accumulation of this difference.

When the stop pins 59 and 60 come into contact and stop the movement of contacts 19 and 20, contact 17 is also stopped and shaft 9 is forced from its biased position relative to receiver 5 until contact 24 engages either contact 26 or 27 and the motor 36 comes into action as explained in connection with Fig. 1.

When contacts 19 and 20 are thus displaced from their central position the centralizing force resulting from the springs 54 is substantially proportional to the displacement. As the response from motor 13 causes contact 17 to move from its engaging contact the springs 54 will move the engaging contact toward the central position. This motion will be opposed by the drag disc 57 so that the rate at which the contacts return to their central position is proportional to their displacement. The motor 13 can therefore remove the error only at the rate at which the contacts return to their central position. During the return of the contacts 19 and 20 to their central position the shaft carrying contact 17 is limited to the same rate. This shaft represents the error between the response from servo-motor 13 and the receiver 5 and therefore the error can only be removed at a rate which is determined as a function of the displacement, that is, of the error.

This speed control in attaining synchronism is the subject matter of my copending application Serial No. 432,237.

It is obvious that the principle exemplified in the illustrated embodiments of the invention may be otherwise applied without departing from the scope of the invention as defined in the following claims.

I claim:

1. A position reproducing mechanism comprising coarse and fine receivers of a self synchronous transmission system having a predetermined ratio of relative movement, a servo-motor, an energizing circuit for the servo-motor including a movable contact, operating means for the movable contact having a yieldable drive connection with and biased to a definite angular relation to the fine receiver, a response connection from the servo-motor operative to neutralize the effect of the operating means upon the movable contact, a pair of movable contactable elements one coupled to be driven by the coarse receiver and the other coupled to be driven in the same direction by the contact operating means at the said predetermined ratio of movement thereto, the said elements being positioned a definite distance out of contact when the contact operating means is in its biased relation to the fine receiver, and means actuated by the engagement of the contactable elements for supplementing the bias of the operating means.
2. A position reproducing mechanism comprising coarse and fine receivers of a self synchronous transmission system having a predetermined ratio of relative movement, a servo-motor, an energizing circuit for the servo-motor including a movable contact, operating means for the movable contact, drive means yieldably connecting the contact operating means and the fine receiver and including a cam and a spring pressed follower biasing the parts to a definite angular relation and operative to reverse the angular direction of bias when a limited departure from biased relation is exceeded, a response connection from the servo-motor operative to neutralize the effect of the operating means upon the movable contact, a pair of movable contactable elements one coupled to be driven by the coarse receiver and the other coupled to be driven in the same direction by the contact operating means at the said predetermined ratio of movement thereto, the said elements being positioned a definite distance out of contact when the contact operating means is in its biased relation to the fine receiver, and means actuated by the engagement of the contactable elements for applying a predominant bias to the operating means to prevent reversal.
3. A position reproducing mechanism comprising coarse and fine receivers of a self synchronous transmission system having a predetermined ratio of relative movement, a servo-motor, energizing means for the servo-motor including a movable control member, operating means including a relief cam operatively connecting the rotor of the fine receiver with the control member, response means operated by the servo-motor for neutralizing the action of the fine receiver rotor upon the control member, a pair of contacts movable in a common path, one coupled to be driven by the coarse receiver and the other coupled to be driven in the same direction by the control member operating means at the said predetermined ratio of movement thereto, the said pair of contacts being spaced a definite distance when the fine receiver rotor and the control member operating means are in synchronism, the relief cam permitting departure from synchronism sufficiently to allow the pair of contacts to engage, an auxiliary motor, an energizing circuit for the auxiliary motor including the pair of contacts, and means operatively connecting the auxiliary motor to the control member operating means.

4. A position reproducing mechanism comprising coarse and fine receivers of a self synchronous transmission system having a predetermined ratio of relative movement, a servo-motor, energizing means for the servo-motor including a movable control member, operating means including a relief cam operatively connecting the rotor of the fine receiver with the control member, response means operated by the servo-motor for neutralizing the action of the fine receiver rotor upon the control member, a pair of contacts movable in a common path, one coupled to be driven by the coarse receiver and the other coupled to be driven in the same direction by the control member operating means at the said predetermined ratio of movement thereto, the said pair of contacts being spaced a definite distance when the fine receiver rotor and the control member operating means are in synchronism, the relief cam permitting departure from synchronism sufficiently to allow the pair of contacts to engage, an auxiliary motor, an energizing circuit for the auxiliary motor including the pair of contacts, means operatively connecting the auxiliary motor to the control member operating means, a normally open clutch in the said connecting means, and means controlled by the said pair of contacts for closing the clutch.

5. A position reproducing mechanism comprising coarse and fine receivers of a self synchronous transmission system having a predetermined ratio of relative movement, a servo-motor, energizing means for the servo-motor including a movable control member, operating means for the control member, a relief drive connecting the control member operating means and the rotor of the fine receiver and including a cam and a spring pressed follower biasing the said operating means and rotor to a definite angular relationship at which the movable control member is synchronized with the said rotor and yieldable to permit departure from synchronism, response means operated by the servo-motor for neutralizing the action of the fine receiver rotor upon the control member, a pair of contacts movable in a common path, one coupled to be driven by the coarse receiver and the other coupled to be driven in the same direction by the control member operating means at the said predetermined ratio of movement thereto, the said pair of contacts being spaced a definite distance when the fine receiver rotor and the control member operating means are in synchronism, whereby the contacts may engage as the yieldable parts permit departure from synchronism, an auxiliary motor, an energizing circuit for the auxiliary motor including the pair of contacts, and means operatively connecting the auxiliary motor to the contact operating means.

6. A position reproducing mechanism comprising coarse and fine receivers of a self-synchronous transmission system having a predetermined ratio of relative movement, a servo-motor, energizing means for the servo-motor including a movable control member, operating means for the movable control member having a yieldable drive connection with and biased to a definite angular relation to the fine receiver and having a response connection from the servo-motor, a pair of relatively movable control elements coupled to be relatively moved by the coarse receiver and the control member operating means at the said predetermined ratio of relative movement, and means actuated by the pair of control elements for supplementing the

bias of the operating means when the relative movement of the control elements exceeds a predetermined amount.

7. A position reproducing mechanism comprising coarse and fine receivers of a self synchronous transmission system having a predetermined ratio of relative movement, a servo-motor, energizing means for the servo-motor including two relatively movable, cooperative control members, operating means for one of the movable control members having a yieldable drive connection with and biased to a definite angular relation to the fine receiver, a response connection from the servo-motor to the said movable control member, the second movable control member being adjustably mounted, means biasing the adjustable control member toward a position to effect positional agreement between the operating means and the servo-motor, means to retard the return movement of the biased member from a displaced position, the control members coacting to displace the adjustable member an amount proportional to the error in positional agreement between the operating means and the servo-motor, a pair of relatively movable control elements coupled to be relatively moved by the coarse receiver and the control member operating means at the said predetermined ratio of relative movement, and means actuated by the pair of control elements for supplementing the bias of the operating means when the relative movement of the control elements exceeds a predetermined amount.

8. A position reproducing mechanism comprising coarse and fine receivers of a self synchronous transmission system having a predetermined ratio of relative movement, a servo-motor, means for energizing the servo-motor including primary and secondary contacts, operating means having a yieldable drive connection with and biased to a definite angular relation to the fine receiver, a response connection from the servo-motor coacting with the operating means to position the primary contact, a pair of movable contactable elements one coupled to be driven by the coarse receiver and the other coupled to be driven in the same direction by the operating means at the said predetermined ratio of movement thereto, the said elements being positioned a definite distance out of contact when the operating means is in its biased relation to the fine receiver, means actuated by the engagement of the contactable elements for supplementing the bias of the operating means, the secondary contact being yieldably biased to open contact relation to the primary contact when the operating means and the response connection are in positional agreement, the two contacts coacting to effect a displacement of the secondary contact an amount proportional to an error in said positional agreement, and means to retard the return of the secondary contact to the biased position when displaced therefrom.

9. A position reproducing mechanism comprising coarse and fine receivers of a self synchronous transmission system having a predetermined ratio of relative movement, control operating means having a yieldable drive connection with and biased to a definite angular relation to the fine receiver, a pair of relatively movable control elements coupled to be relatively moved by the coarse receiver and the control operating means at the said predetermined ratio of relative movement, means actuated by the pair of control elements for supplementing the bias

of the control operating means when the relative movement of the control elements exceeds a predetermined amount, a servo-motor operably connected to drive a response shaft, means differentially connecting the control operating means and the response shaft to actuate a control for the servo-motor to bring the response shaft into angular agreement with the control

operating means, and means associated with the control for the servo-motor effective to cause the servo-motor to bring the response shaft into angular agreement with the control operating means at a rate which is a function of the lack of angular agreement of the response shaft with the control operating means.

JAMES D. TEAR.
